ABSTRACT: A device primarily intended for explosive destruction of hard rocks which employs a liquid high-explosive three-component mixture. The constructive design of the apparatus enables the production of a series of successive blasts controllable by their strength and by the frequency of their succession.

FIG. 2

BLASTING APPARATUS

The present invention relates to blasting apparatus employing liquid explosive material having for its components fuel and an oxidizer, fired as a mixture under the action of liquid initiator.

Used as an oxidizer can be nitrogen tetroxide, nitric acid, tetrinitromethane, and as fuel—kerosene, benzine, aniline, and toluene; as an initiator there can be used an eutectic alloy of potassium and sodium, and hydrazine.

The apparatuses of this type are known as jet-type blasting apparatus which can be used for destruction of rocks, for explosive forming under a layer of liquid in open dies and in other fields of technique where the energy of blast can be used.

From the earlier publications, in particular from the USSR author's certificate No. 122,107, there is known a blasting apparatus using liquid explosive and liquid initiator, and designed for boring holes. Said known apparatus is provided with a head having inlet channels for separate delivery of liquid components and liquid initiator supplied to the liquid explosive for its detonation.

The reservoirs for liquid explosive components and initiator are arranged in the apparatus housing above the head with the channels, batching the liquid components and initiator being effected with the aid of valves provided at the inlet end of the channels and secured to a spring-loaded crossbeam. When the doses of liquid explosive are alternately fired, the shock wave forces out the crossbeam with the valves and subsequent doses of explosive components and initiator pass through clearances appearing after the displacement of valves and via the channels to the hole face wherein the mixing of components and their firing is going on under the action of the initiator.

The known apparatuses do not provide for a possibility of control over the working process. The supply and batching of components and initiator are of occasional nature and depend on explosion parameters of each dose of the explosive. Stronger explosions bring about an increase of time required for opening the valves and for injecting a greater dose of explosive material into the hole face, which may finally bring about the breakage of the blasting apparatus.

An object of the invention is to eliminate the above-mentioned disadvantages of said known apparatus.

The present invention is aimed at the provision of a blasting apparatus with a prompt control system facilitating the control over the explosion process.

Described hereinbelow is a blasting apparatus, mainly for destruction of rocks, using liquid explosive materials and consisting of a head with channels for delivery of the explosive components and the liquid initiator, said channels being alternately closed by valves. According to the invention, the apparatus comprises a pulse generator which controls the drive of the valve closing the channel for delivery of the initiator, and a sensing unit serving to register the blast, in particular, an accelerometer which transmits a signal to the blast control unit, said unit being operatively connected with the drives of the valves closing the component supply channels and with a drive of the valve closing the channel for delivery of the initiator.

According to the invention, the blast control unit has a device for controlling the explosion strength and a device for counting misfires in a series on whose command there operate said valves cutting off the delivery of components and initiator.

The invention makes it possible to steadily carry out the explosion process and facilitates the operation of the apparatus.

The invention is further explained by the following description of an exemplary embodiment thereof in conjunction with the accompanying drawings, wherein:

FIG. 1 is a schematic diagram of the blasting apparatus; and FIG. 2 is a block diagram of the blasting apparatus control system, according to the invention.

Referring to FIG. 1, the blasting apparatus comprises reservoirs 1 and 2 for fuel and oxidizer which are the components of liquid explosive material, and reservoir 3 for liquid initiator, all respectively connected by pipelines 4, 5 and 6 with apparatus head 7. Fuel and oxidizer are delivered from reservoirs 1 and 2 to apparatus head 7 with the aid of pumps 8 and 9, and the initiator is supplied from reservoir 3 under the action of compressed air in receiver 10 connected with reservoir 3.

Head 7 is provided with outlet channels 11, 12 and 13 (FIG. 2) for separate delivery of fuel, oxidizer and initiator, which channels are connected with pipelines 4, 5 and 6 and can be closed by valves 14, 15 and 16 mounted therein and provided with individual drives 17, 18 and 19, e.g. with electromagnetic drives. It is evident that said valves can be mounted on supply pipelines 4, 5 and 6.

While the apparatus is in operation, fuel and oxidizer flow continuously, while the initiator for firing the charge is delivered periodically.

To carry out the working process, the apparatus, as shown in FIG. 2, comprises pulse generator 20 controlling drive 19 of valve 16 serving for delivery of the liquid initiator, blast-registering sensing unit 21, preferably an accelerometer secured on apparatus head 7. When fuel and oxidizer are mixed and the mixture is fired by the initiator, there takes place a blast sensed by sensing unit 21 whose signal comes to blast control unit 22.

Unit 22 comprises device 23 for controlling the strength of blast, and device 24 counting misfires in a series and operatively connected with drives 17, 18 and 19 of valves 14, 15 and 16.

Device 24 is necessary because several misfires in a row may bring about an accumulation of a large amount of liquid explosive material capable of breaking the apparatus. This device is supplied with a master pulse from generator 20 and with a signal from device 23 for controlling the strength of a blast. In case, no signals come from sensing unit 21 that the blast has occurred device 24 collects the data on unrealized master pulses up to a certain value. When the number of misfires is greater than a certain value, device 24 sends a signal to drives 18, 17 and 19 of valves 14, 15 and 16, which close channels 11, 12 and 13 in apparatus head 7, thus cutting off the delivery of explosive components and the initiator.

Thus, the invention provides for the control over the explosion process, insures the safety of operation, and makes it possible to control the strength of each blast.

50 I claim:

1. A blasting apparatus using liquid explosive materials, comprising: a head provided with channels for delivering explosive components and a liquid initiator; valves closing said channel; means for driving said valves; a pulse generator controlling the drive of the valve associated with the channel for delivery of the liquid initiator; a sensing unit serving to register a blast; a blast control unit operatively connected with said valve driving means, said blast control unit being actuated by receipt of a signal from said blast-registering sensing unit.

55 2. A blasting apparatus as claimed in claim 1, wherein said blast control unit comprises a device for controlling the strength of a blast and a device for serially counting misfires, the latter device operating by sending a command for the operation of said valves cutting off the delivery of explosive components and initiator.

60 3. A blasting apparatus as claimed in claim 1 wherein the sensing unit is an accelerometer.
